UNITED STATES PATENT OFFICE

98,266

DESIGN FOR A SHAVING BOWL

Jacques Manoha, New York, N. Y., assignor to Houbigant, Inc., New York, N. Y., a corporation of New York

Application November 29, 1935, Serial No. 59,821

Term of patent 14 years

To all whom it may concern:

Be it known that I, Jacques Manoha, a citizen of the Republic of France, residing in the city of New York, county of New York, and State of New York, have invented a new, original, and ornamental Design for a Shaving Bowl, of which the following is a specification, reference being had to the accompanying drawing, forming a part thereof,

In the drawing:—

Fig. 1 is a side elevation of a shaving bowl, showing my new design.

Fig. 2 is a top plan view thereof.

I claim:—

The ornamental design for a shaving bowl substantially as shown.

JACQUES MANOHA.
